SKI HARNESS

Robert Purvis, Saranac Lake, N. Y.

Application January 30, 1948, Serial No. 5,402

5 Claims. (Cl. 280—11.35)

1

This present invention relates to a ski harness of the hinge action type.

The main object of my invention is the design of a ski harness having a rigid part fixed to the ski, that is adjustable to various sizes of boots, including rubber boots, is of simple construction and may be manufactured at low cost.

It is a further object of this invention to design a ski harness having toe plates which because of their swivel mounting prevent the cutting of rubber foot wear and that is so constructed that pressure in turning and twisting the ski is applied at the heel as well as at the toe.

In the drawings:

Figure 1 is a side view of my ski harness attached to the foot;

Figure 2 is a top plan view;

Figure 3 is a central longitudinal section;

Figure 4 is a bottom plan view;

Figures 5 and 6 are enlarged transverse vertical sections on line 5—5 and 6—6 respectively of Figure 2;

Figure 7 is a transverse section on line 7—7 of Figure 1;

Figure 8 is a vertical detail section through one of the rear stops of the heel on line 8—8 of Figure 2.

In the drawing in which like reference characters designate like or similar parts, there is shown at 2 the central portion of the ski preferably of wood which supports a heel 3 of any suitable material preferably metal.

The bottom surface 4 of the heel 3 is preferably corrugated to prevent lumping of the snow. An aperture 5 extends horizontally and lengthwise through the heel to house a guide 6 which extends forwardly and is pivoted at the forward end to a plate 7. The latter is secured upon the horizontally offset portion of a foot member 8 the lower portion of which is secured by suitable fastening means to the upper surface of the ski. A bridge member 10 is secured to the top of plate 7, extends forwardly in parallelism to the ski and is secured to the horizontally offset portion of foot member 11 which is secured to the ski member.

The rounded rear portion of the heel is provided with a pair of symmetrically arranged stops 12 which take the form of an angle iron held in a hollow of the heel by suitable fastening means 13 and having a pair of legs the outer ends of which protrude beyond the heel and are bent upward (Figures 1, 2 and 8).

The heel is further provided with a horizontal transverse aperture in which the horizontal portions of clamps 14 can slide. The latter include upstanding portions and headed pins 15 secured to the lower side adjacent the inner confronting ends of the horizontal clamp portions and each slidably in one of a pair of rearwardly converging slots 16 formed in a rigid end portion 17 of a strip

2

of belting 18, both overlying the guide 6. The belting extends forwardly over the top surface of the bridge and in a depression 19 (Figure 5) in the latter and then beneath inwardly extending spaced flanges 20 formed on the bridge member (Figures 2 and 7). The front end of the belting is secured to the bottom surface of a plate 21 of a width to fit between the inner edges of the flanges. From the front and rear edges of this plate rise bosses 22 in which a screw shaft 23 is journaled. A nut 24 is threaded upon the shaft and has in its upper portion a hole for a horizontally disposed pivot pin 25 which also passes through the bifurcations of a lever 26 which is offset rearwardly and then forwardly.

The forward portions 27 of the flanges described are bent upward and apertured for the passage of short bolts 28, each of which also passes through the terminals of the outwardly diverging arms of a yoke 29. In the parallel portions of these arms is pivoted a centrally apertured pivot bolt 30. The outer portion of lever 26 beyond the second bend passes through the aperture in the bolt and is encircled by a coil spring 31, bearing with one end against the bolt and with the other end against a nut 32 the turning of which will vary the tension of the spring, upon the free end of the lever.

The intermediate portion of the bridge is supported by a transversely apertured block 33. Into the two ends of this opening are threaded screws 34 after passing through nuts 35 which have inwardly extending guide portions 36 slidable between the upper surface of the block and the overhanging undepressed flanges of the bridge 35 and carrying by vertical pivots 37 on their upper surfaces the horizontal portions of upstanding toe clamps 38. The upper ends of the latter are connected by a strap 39. A similar strap connects the upper ends of the heel clamps 14. Each of the straps 39 is of a conventional construction including complementary end portions which are adjustably connected by a suitable buckle or fastening, not shown.

The toe clamps 38 need only be adjusted once ordinarily for use by a skier and which may be readily accomplished by the sole of the shoe being positioned on the bridge member 10 and with the heel resting on the heel block 3 and abutting against the heel stops 12, as illustrated in Figure 1 except that the heel block 3 will be resting on the top surface of the ski portion 2. The two toe clamps 38 are then positioned in abutting engagement with the side edges of the sole of the skier's shoe after which the screws 34 are advanced through the nuts 35 into engagement with the transverse threaded bore of the block 33 so that the parts will be in the positions as illustrated in Figure 5 and correctly adjusted to fit the shoe sole. The toe strap 39 may then be properly adjusted to fit snugly across the upper surface of

the toe portion of the shoe and the heel of the shoe may then be elevated relatively to the block 3 and out of engagement with the heel stops 12 so that the toe portion of the shoe may then be extracted rearwardly from a position between the toe clamps 38 and beneath the toe strap 39. Thereafter, in applying and securing the shoe encased foot to the ski, the toe portion is inserted between the toe clamps 38 and beneath the toe strap 39 and as it is advanced forwardly or from left to right of Figure 1 the side edges of the sole will engage the forward edges of the toe clamps for causing said clamps to oscillate about their pivots 37 and to be thereby brought into flush engagement with the side edges of the shoe sole and when thus disposed the toe strap will be positioned relatively tight across the upper surface of the toe of the shoe and the shoe will be disposed so that the shoe heel and rear portion of the shoe may be swung downwardly to position the shoe heel against the heel block 3 and in abutting engagement with the heel stops 12. These operations are accomplished while the toggle lever 29 is swung upwardly and rearwardly from right to left of its position of Figure 3 so that the belting 18 and its rigid end portion 17 will be displaced rearwardly or from right to left of their positions of Figure 3, in order that the heel clamps 14 will be displaced laterally outwardly of one another to spread positions by the cam means 15, 16. Accordingly, after the heel has been positioned against the block 3 the toggle lever 29 is swung forwardly or back to its position of Figure 3 to thereby displace the belting 18 and its rigid portion 17 forwardly or from left to right of Figure 3 so that the heel clamps 14 will be drawn inwardly of one another by the cam means 15, 16 and into clamping engagement with the side edges of the shoe heel. Thereafter, the heel strap ends may be buckled across the instep of the shoe to complete the fastening of the shoe to the ski.

In removing the shoe from the ski, the rear heel strap 39 is first unfastened and the toggle joint lever 29 is then swung rearwardly or from right to left of Figures 1 and 3, as previously described, to displace the heel clamps 14 away from one another, as aforescribed, so that the shoe heel can be lifted out of engagement with the stops 12 and the shoe then displaced rearwardly out of engagement with the toe strap 39 and toe clamps 38, as previously described.

While I have above described in detail the specific embodiment of my invention illustrated in the accompanying drawings, I do not desire my invention to be limited to the particular construction disclosed and I intend in the appended claims to cover all modifications within the spirit and scope of my invention.

What I claim as new and desire to secure by Letters Patent is:

1. A ski harness comprising a support adapted to be attached to the upper surface of the intermediate portion of a ski, a heel guiding means pivotally connected to said support and extending rearwardly therefrom, a heel supporting member slidably mounted on the heel guiding means for sliding movement toward and away from said support, said heel supporting member having upstanding rear heel stops, heel clamping members slidably connected to the heel supporting member, cam means slidably connected to the heel clamping members and slidably in said heel supporting member in a direction at right angles to the direction of sliding movement of the

clamping members relatively to the heel supporting member, a flexible member connected to said cam means and extending forwardly therefrom, a spring pressed toggle means pivotally connected to the support and to said flexible member for exerting a pull on the flexible member when the toggle means is swung in one direction to draw the heel clamping means toward one another and into clamping position and for displacing the heel supporting member toward said support to move the rear heel stops in the same direction, and toe clamping means mounted for lateral and angular adjustments on said support.

15 2. A ski harness as in claim 1, said spring toggle means, when swung in said aforementioned direction, being movable to a position for locking the heel clamping members in engaged positions.

20 3. A ski harness as in claim 1, said spring toggle means being disposed forwardly of the heel supporting member for yieldably urging said heel supporting member toward the toe clamping means when the heel clamping members are retained thereby in a clamping position.

4. A ski harness comprising a support adapted to be attached to the upper side of a ski and disposed longitudinally thereof, a guide bar pivotally connected to one end of said support and extending therefrom for swinging movement in a plane perpendicular to the plane of the ski, a heel block slidably supported on said guide bar for movement toward and away from said support and having upstanding heel engaging stops adjacent the end thereof remote to the support, laterally adjustable heel clamping members slidably mounted in and connected to said heel block for movement transversely thereof, cam means slidably disposed in said heel block for movement longitudinally of the guide bar and connected to said heel clamping members for displacing the

35 40 45 50 55 60 heel clamping members toward one another when said cam means is moved in a direction toward the support, spring pressed toggle means pivotally connected to the support adjacent its opposite end for swinging movement longitudinally thereof, a flexible member connecting said spring toggle means and cam means for displacing said cam means toward the support when said toggle means is swung in a direction away from the heel block and for locking the heel clamping members in clamping positions, said heel block being connected to the flexible member by the heel clamping members and the cam means and being displaceable toward said support by swinging movement of the toggle means away from the heel block, and toe clamping means slidably connected to said support and laterally adjustable relatively thereto.

5. A ski harness as in claim 4, said toe clamping means being swivelly supported for angular adjustment relatively to the support.

ROBERT PURVIS.
